UNITED STATES PATENT OFFICE.

SAMUEL HERBERT HOUGHTON, OF HARVARD, MASSACHUSETTS.

SHEAVE FOR SLIDING DOORS.

SPECIFICATION forming part of Letters Patent No. 288,338, dated November 13, 1883.

Application filed September 5, 1883. (No model.)

To all whom it may concern:

Be it known that I, SAMUEL HERBERT HOUGHTON, of Harvard, in the county of Worcester, in the Commonwealth of Massachusetts, have invented a new and useful Improvement 5 in Doors and Trucks Therefor; and I do hereby declare the same to be described in the following specification and represented in the accompanying drawings, of which—

10 Figure 1 is a front elevation, and Fig. 2 a vertical and transverse section, of the lower portion of a door with my improved truck applied thereto. Fig. 3 is a front view, Fig. 4 an end view, Fig. 5 a rear view, and Fig. 15 6 a transverse section, of the truck.

The nature of my invention is defined in the claims hereinafter presented.

The trucks of heavy stable or sliding doors are usually applied and bolted to one of the 20 sides of the door without their wheels being extended within the frame, as is the case with my improvement, in which the door or the lower girt of the frame thereof is recessed to receive the upper half or portion of the wheel 25 of each truck, and such wheel is sustained by a tri-armed supporter slotted in its arms, and provided with a door-bearing extending from the median arm.

In the drawings, A denotes a portion of a 30 door at and near one of its lower corners, a being the lower girt of the door-frame and b one of its stringers, such girt being tenoned into the stringer. The said girt has a semi-circular or segmental recess, c, made in it from 35 its lower edge upward, as represented, the wheel d of the truck B being inserted in such recess so as to project into and downward from it. The said wheel is to revolve on a journal, e, extending from the tri-armed supporter f, 40 whose median arm is at right angles to the

other arms. In each arm there is a vertical slot, g, and from the median arm there extends rearward over the wheel a flange or bearing, h, on which the girt of the door is to rest or bear either directly or by a piece of wood or 45 other proper material inserted between them. Screw-bolts i going through the door pass through the slots g and have nuts k screwed on them and against the tri-armed supporter. While the said slots admit of the supporter 50 being adjusted vertically to raise the door in case of sagging of it, or for any other purpose, the bearing h prevents the weight of the door from causing the truck to accidentally move upward relatively to the door. By recessing 55 the girt and placing the wheel in the recess, so as to carry the median plane of the wheel in that of the door or thereabout, the weight of the door is brought directly over the wheel, whereby the door is caused to run to advantage or with less friction than is generally the case when the truck is wholly on one side of the door.

I claim—

1. The door-frame recessed to receive the 65 truck-wheel, in combination with such wheel and with its tri-armed supporter having slots in its arms, as and for the purpose described, such wheel and supporter being arranged with each other and with the door-frame, substantially 70 as set forth.

2. The tri-armed supporter provided with the fastening-slots in its arms, and with the door-bearing extending from the median arm and over the wheel, substantially as represented. 75

SAMUEL HERBERT HOUGHTON.
